CLAIM

The ornamental design for a fluid transfer connector as shown and described.

DESCRIPTION

FIG. 1 is a front, top, and left side perspective view of an embodiment of the fluid transfer connector, showing the new design;

FIG. 2 is a rear side elevational view thereof;

FIG. 3 is a front side elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a bottom front side perspective view thereof;

FIG. 9 is a front, top, and left side perspective view of another embodiment of the fluid transfer connector, showing the new design;

FIG. 10 is a rear side elevational view thereof;

FIG. 11 is a front side elevational view thereof;

FIG. 12 is a right side elevational view thereof;

FIG. 13 is a left side elevational view thereof;

FIG. 14 is a top plan view thereof;

FIG. 15 is a bottom plan view thereof; and,

FIG. 16 is a bottom front side perspective view thereof.

In the drawings, the broken lines are for the purpose of illustrating portions of the fluid transfer connector which form no part of the claimed design.
